COTTON PICKER

Application filed April 12, 1928. Serial No. 269,552.

This invention relates to cotton pickers and more particularly to pickers of the type utilizing a reciprocatory barbed stem or finger to gather the fiber.

Pickers of this general type have been known and tried for many years, but have not proven entirely successful because of certain defects which have developed in practical operation. Among these defects is the difficulty of properly removing or stripping the fiber from the barbed stem or finger, the fiber having a tendency to become packed and jammed into the barbs so that it is not easily dislodged.

One of the objects of the present invention is to provide a picker finger so designed and constructed that the fiber will not become packed in the barbs.

Another object is to provide, in combination with such a reciprocatory finger, a stripper plate having flaring or funnel shaped openings therein through which the fingers work, whereby the sharp edge of such openings serves to effectively strip or remove the accumulated fiber from the fingers.

In order that the invention may be readily understood, reference is had to the accompanying drawing, forming part of this specification, and in which:

Figure 1 is a fragmentary plan view showing several of our improved fingers associated with a pair of stripper plates;

Figure 2 is a fragmentary face view of one of these stripper plates showing the ends of the fingers in position in the openings therein;

Figure 3 is a side elevation on an enlarged scale, showing one of our improved picker fingers and the adjacent portion of the stripper plate, the latter being shown in section;

Figure 4 is a transverse section on the line 4-4 of Figure 3, on a still further enlarged scale;

Figures 5 and 6 are a fragmentary face view and section respectively, on the same scale as Figure 3, of a modified form of stripper plate opening; and

Figure 7 is a fragmentary longitudinal section on the line 7-7 of Figure 4, looking in the direction of the arrows.

Referring to the drawing in detail the numeral 1 designates our improved picker finger in its entirety. Each finger is preferably provided at one end with a reduced screw threaded shank 2, by means of which the fingers may be mounted in a suitable frame 11, as shown in Figure 1, and secured in position, as by means of nuts 12. Referring again to Figure 1, it will be seen that we preferably employ two sets of fingers, each set secured to a reciprocatory frame 11, and each frame being associated with means including a pitman rod 13 by means of which it may be reciprocated.

Referring now to Figures 3 and 4, the construction of the finger itself will be described. As shown in the drawing, the body of the finger is in the form of an elongated cylinder having longitudinally extending channels 3 formed therein, these channels having ribs 9 between them. By reference to Figure 4, it will be seen that each channel is bounded by two plane side walls 4 and 5, the first being substantially radial and relatively short, while the second is preferably disposed at approximately right angles to the first and is relatively long.

In the bottom of each such channel is cut a rectangular groove 6, the sides of such groove being disposed at an angle to the side walls 4 and 5 of the channel. In each such groove are set a series of barbs, longitudinally spaced apart and each consisting of a needle 7 having a point 8 bent upwardly and extending at an angle, as clearly shown in Figure 7. In practice, these needles or barbs may be rigidly mounted in the grooves 6 by making the grooves slightly smaller than the diameter of the needles and then forcing the needles in under pressure. Further, for the sake of additional security, the extreme edge of the groove adjacent the needle may be slightly deformed or upset, as shown at 10 in Figure 4, so as to overlie the body of the needle and prevent it from coming out of the groove.

Referring again to Figure 4, it will be seen that the ribs 9 constitute guards or shields which prevent the stems and leaves of the cotton plant from being caught by the barbs,

the points 8 of the barbs being no higher than, and preferably lying slightly below, a line tangent to the two adjacent ribs.

It will be particularly noted that the walls 4 and 5 of each channel, and particularly the wall 5, are so shaped and disposed as to provide a relatively wide space within which the cotton fiber is received. Preferably the points of the barbs are not disposed angularly midway between the two walls 4 and 5, but, as shown in Figure 4, lie much closer to the short radial wall 4, than to the other. This further increases the large open space adjacent the wall 5, and thus tends to prevent the fiber from packing or jamming in such space and facilitating its ready removal from the barbs and channels.

In use, a pair of substantially vertical stripper plates 14, preferably having flaring forward ends, as shown at 14^a in Figure 1, are disposed between the sets of reciprocating fingers, and each of such plates is provided with a series of holes or openings 15, arranged to register with the adjacent fingers.

By reference to Figure 3, it will be seen that that side of the holes or openings 15 remote from the fingers is made flaring or funnel shaped, and that the inner edges of such openings are preferably serrated or provided with saw-teeth as shown at 16.

It will be understood that in use, the machine carrying the reciprocating fingers and stripper plates is moved along through the field in such a way that the cotton plants pass between the plates 14. The fingers, after they have been projected through the openings 15 into such space, return and carry with them the cotton fiber which is picked up by the barbs. Owing to the funnel shape of the holes 15, the adhering fiber is readily drawn outward through these holes, but upon the return stroke of the fingers, the sharp serrated edges of the openings engage the fiber and push or strip it from the barbs, as will be obvious. This stripped fiber then falls into a suitable receptacle or is carried away by belts. It will be noted that there is considerable clearance between the body 50 of the finger and the edge of the opening 15, thus permitting large tufts or bunches of fiber to be readily drawn through such opening.

Instead of making the openings with serrated edges, as shown in Figure 3, we may employ funnel shaped openings with straight or smooth edges, as shown at 15' in Figures 5 and 6, both types of opening having been found effective.

It will be noted that our improved independently formed barbs are spaced apart longitudinally of the finger and we find that this arrangement gathers and holds the fiber much more effectively and to much better advantage than the type of barb hereto-

fore employed consisting of a continuous strip having saw teeth at its edge. Our improved barb, in combination with the special form of channel in which it is mounted, provides a large fiber receiving space which has proven, in practice, very efficient.

What we claim is:—

1. In a cotton picker, the combination with a barbed reciprocatory finger, of a fixed stripper plate having an opening through which said finger is adapted to freely reciprocate, the inner margin of said opening being flaring or funnel shaped, and spaced from said finger.

2. In a cotton picker provided with a barbed reciprocatory finger, a fixed stripper plate having an opening through which said finger is adapted to freely reciprocate, the margin of said opening being flaring or funnel shaped, and the edge serrated.

3. A cotton picker finger comprising an elongated body having longitudinal channels formed therein, and a series of independent spaced barbs, circular in cross-section, set in the bottom of each channel.

4. A cotton picker finger comprising an elongated body having longitudinal channels formed therein, a groove cut in the bottom of each channel, and a series of independent separately formed barbs set in said groove with their points only projecting therefrom, said barbs lying wholly within said channel.

5. A cotton picker finger comprising an elongated body having longitudinal channels formed therein, a groove cut in the bottom of each channel, and a series of independent barbs, set in said grooves, each barb consisting of a separately formed needle lying in the groove, and having its point bent upwardly and extending at an angle.

6. A cotton picker finger comprising an elongated body having longitudinal channels formed therein, and a series of independent, separately formed barbs mounted within each of said channels, the point of each barb lying substantially nearer one wall of the channel than the other.

7. A cotton picker finger comprising an elongated body having longitudinal channels formed therein and having plane side walls, one of which is substantially shorter than the other, and a series of barbs mounted within each of said channels and having their points lying nearer the shorter wall.

8. A cotton picker finger comprising an elongated body having longitudinal channels formed therein and having plane side walls, one of which is substantially radial and relatively short, and the other of which lies at approximately right angles to the first and is relatively long, and a series of barbs mounted within each of said channels, and having their points in proximity to the

short radial wall, and remote from the other or long wall.

In testimony whereof we affix our signatures.
